UNITED STATES PATENT OFFICE.

GEORGE GASPAR, OF PINEHILL, PENNSYLVANIA.

DESIGN FOR A COMBINED COFFEE AND TEA POT.

50,779.

Specification for Design.

Patented May 15, 1917.

Application filed February 26, 1917. Serial No. 151,134. Term of patent 14 years.

To all whom it may concern:

Be it known that I, GEORGE GASPAR, a subject of the King of Hungary, residing at Pinehill, in the county of Somerset and State of Pennsylvania, have invented a new, original, and ornamental Design for a Combined Coffee and Tea Pot, of which the following is a specification, reference being had to the accompanying drawing, forming part thereof.

The figure is a view in perspective of a combined coffee and tea pot, showing my new design.

I claim:

The ornamental design for a combined coffee and tea pot, as shown.

GEORGE GASPAR.

Witnesses:

HARRY PHILLIPS,
GEO. L. HUSTON.
